Primary Examiner — Cynthia Ramirez

CLAIM

The ornamental design for a wheeled cart, as shown and described.

DESCRIPTION

FIG. 1 illustrates top perspective view of a wheeled cart, according to a first embodiment.

FIG. 2 illustrates a front view of the wheeled cart illustrated in FIG. 1.

FIG. 3 illustrates a back view of the wheeled cart illustrated in FIG. 1.

FIG. 4 illustrates a first side view of the wheeled cart illustrated in FIG. 1.

FIG. 5 illustrates a second side view of the wheeled cart illustrated in FIG. 1.

FIG. 6 illustrates a top view of the wheeled cart illustrated in FIG. 1.

FIG. 7 illustrates a bottom view of the wheeled cart illustrated in FIG. 1.

FIG. 8 illustrates a bottom perspective view of the wheeled cart illustrated in FIG. 1.

FIG. 9 illustrates a top perspective view of the wheeled cart illustrated in FIG. 1.

FIG. 10 illustrates an exploded view of the hitch of the wheeled cart illustrated in FIG. 1.

FIG. 11 illustrates top perspective view of a wheeled cart, according to a second embodiment.

FIG. 12 illustrates a front view of the wheeled cart illustrated in FIG. 11.

FIG. 13 illustrates a back view of the wheeled cart illustrated in FIG. 11.

FIG. 14 illustrates a first side view of the wheeled cart illustrated in FIG. 11.

FIG. 15 illustrates a second side view of the wheeled cart illustrated in FIG. 11.

FIG. 16 illustrates a top view of the wheeled cart illustrated in FIG. 11.

FIG. 17 illustrates a bottom view of the wheeled cart illustrated in FIG. 11.

FIG. 18 illustrates a bottom perspective view of the wheeled cart illustrated in FIG. 11.

FIG. 19 illustrates a top perspective view of the wheeled cart illustrated in FIG. 11; and,

FIG. 20 illustrates an exploded view of the hitch of the wheeled cart illustrated in FIG. 11.

The hitch is shown separated in FIGS. 10 and 20 to show aspects of the design that are not visible combined.

The broken lines in the figures show portions of the wheeled cart form no part of the claimed design. The surface shading lines show contours and are not surface ornamentation.
